UNITED STATES PATENT OFFICE.

RAY E. DE CAMP, OF WILKINSBURG, PENNSYLVANIA, ASSIGNOR TO WESTINGHOUSE ELECTRIC & MANUFACTURING COMPANY, A CORPORATION OF PENNSYLVANIA.

SYSTEM OF CONTROL.

Application filed November 20, 1919. Serial No. 339,511.

My invention relates to control systems and particularly to systems for controlling the sequence of operation of a plurality of electromagnetic switches for controlling the 5 operating circuits of dynamo-electric machines.

The object of my invention is to provide a simplified system of the above-designated character.

Figure 1 of the accompanying drawing is 10 a diagrammatic view of a control system embodying my invention, and Fig. 2 is a diagrammatic view of a portion of a control system illustrating a different application 15 of the principles embodied in my invention.

The control system illustrated in Fig. 1 embodies a motor 1; a starting resistor 2 for controlling the value of current traversing the circuit of the motor 1; a circuit 20 breaker 3 for connecting the system to a source of energy; a plurality of contactors 4, 5, 6 and 7 that are respectively actuated by coils 8, 9, 10 and 11 to shunt portions of the resistor 2; and relays 12 and 13 that 25 control the sequence of operation of the contactors.

Resistor 2 is a form of starting rheostat usually employed for accelerating electric 30 motors. The electromagnet coils 8, 9, 10 and 11 respectively actuate the contactors 4, 5, 6 and 7 when the coils are energized to a predetermined degree. The contactors 35 5 and 6 are provided with interlocks 14 and 15 which respectively establish circuits for coils 10 and 11.

The relays 12 and 13 are actuated to their 40 open positions by a current of predetermined value traversing the corresponding actuating coils 16 and 17 that are in series with different portion of the main motor circuit. The relays 12 and 13 are respectively adapted to shunt resistors 18 and 19. The resistor 18 is in series-circuit relation 45 to coil 8 and interlock 14, and the resistor 19 is connected in series-circuit relation to coil 9 and interlock 15.

The resistors 18 and 19 are of such value 50 that the energy supplied to the several contactor-actuating coils 8, 9, 10 and 11 through the corresponding resistor, is not sufficient to actuate the contactors to their closed positions but is sufficient to maintain them in these positions after they have been closed by a current of larger magnitude.

In order to operate the system illustrated

in Fig. 1, the circuit breaker 3 is closed to energize the system. The initial rush of current through armature 1 and resistor 2 actuates relay 12 to an open position and inserts resistor 18 in series relation with 60 the coil 8 of the contactor 4. The insertion of the resistor 18 in the circuit of the coil 8 insures a degree of energization of the coil that is not sufficient to actuate the contactor 4 to its closed position and the same is, therefore, maintained in its open position until the current traversing motor armature 1 decreases to a predetermined value that is 65 sufficiently small to permit relay 12 to close. The resistor 18 is thereby shunted from the 70 coil circuit, and the total voltage across the motor armature and resistor 2 is applied to the actuating coil 8. The contactor 4 then closes to complete a shunt circuit for a portion of the resistor 2.

It will be noticed that, at this step in the sequence of operation of the control system, the main motor current is diverted from the actuating coil 16 of the relay 12 and traverses the actuating coil 17 of the relay 13. 80 Relay 12 is, therefore, maintained in its closed position during this period of transition, and relay 13 is actuated to its open position by the rush of current caused by the closing of contactor 4. The opening 85 of the relay inserts the resistor 19 in the circuit of the actuating coil 9. The relay 13 is maintained in its open position until the current traversing its actuating coil decreases to a predetermined value that is 90 sufficiently low to permit its closing. As soon as relay 13 shunts the resistor 19 by dropping to its closed position, contactor 5 is closed, and an additional portion of the 95 resistor 2 is excluded from the circuit of the main motor 1. This operation completes another step in the acceleration of the motor 1.

When the contactor 5 is closed, the current traversing the main motor circuit is again diverted and traverses the portion of the circuit embodying the coil 16 of the relay 12. The heavy armature current actuates the relay 12 to its open position and the resistor 18 is reinserted in the circuit 100 of coil 8. The resistor 18 is of such value that the current traversing the coil 8 of contactor 4, when the resistor 18 is reinserted in the control circuit, is of sufficient value to maintain contactor 4 in its closed position. 110

This current is not, however, of sufficient value to actuate the contactor from its open position to its closed position.

- Contactor 5 is provided with the interlock 5 which completes a circuit for the actuating coil 10 when switch 5 is closed. This controls the sequence of operation of the various switches. Since the main motor current traverses the actuating coil of relay 12 during this period in the operation of the system, the relay 12 is actuated to its open position and the resistor 18 is inserted in series with the actuating coil 10 of contactor 6. 10 When the current traversing the main motor circuit decreases to a predetermined minimum value, the relay 12 again closes to shunt the resistor 18 and thereby effect the closing of contactor 6. This establishes a 20 circuit in shunt relation to an additional portion of the resistor 2.

The main motor current is again diverted to the portion of the circuit containing the actuating coil 17 of relay 13. A circuit for the actuating coil 11 of the contactor 7 is completed by interlock 15 that is closed when contactor 6 is closed. As soon as relay 13 drops to its closed position, the coil 11 is energized to such degree as to close the contactor 7 which completes a shunt circuit for the entire resistor 2.

Fig. 2 shows a portion of a control system embodying a modification of the principles involved in the system illustrated in Fig. 1. 35 The control circuit shown in Fig. 2 comprises a relay 20 that is controlled by the current traversing a main circuit 21 which may be connected to an electric apparatus. A resistor 22, which is similar to resistors 18 and 19 of Fig. 1, is shunted by the relay 20. When the relay 20 is actuated to an open position by a current of predetermined value traversing circuit 21, the resistor 22 is inserted in the control circuit of a plurality of 45 electromagnet coils 23 and 24 for actuating contactors 25 and 26. Connections in the main circuits 27 and 28 are controlled by contactors 25 and 26.

The contactor 25 is provided with an interlocking device 29 that controls the sequence of operation of the two contactors 25 and 26.

The method of operation of the portion of the control circuit illustrated in Fig. 2 is 55 substantially the same as that just described in connection with Fig. 1. The interlocking system is, however, slightly different in that, instead of employing interlocks associated with contactors controlled by one relay 60 to establish a sequence of operation for contactors controlled by a second relay, as in Fig. 1, the circuits shown in Fig. 2 illustrate a method of controlling the sequence of operation of a plurality of contactors controlled 65 by a single relay.

The resistor 22, shown in Fig. 2, is of such value that contactors 25 and 26 are maintained in their closed positions after they have been actuated thereto, but the value of the resistance is sufficiently high to 70 prevent the initial operation of the contactors. Assuming that a current of sufficient value to actuate relay 20 traverses the circuit 21, contactors 25 and 26 are maintained in their open positions until this current decreases to a value sufficiently small to permit the relay to close. Coil 23 then receives full voltage, since the intervening resistor 22 is shunted by relay 20, and contactor 25 is actuated to its closed position to establish 75 certain circuit relations for the main circuit 27.

The interlock 29 completes the circuit for the coil 24 when contactor 25 is closed. If it is assumed that another temporary rush 85 of current traverses circuit 21, by reason of the closure of contactor 25, the contactor 26 is maintained in its open position until the current traversing circuit 21 decreases to a value permitting the relay to close. When 90 the relay 20 closes, contactor 26 establishes certain circuit relations for the main circuit 28.

From the above discussion, it will be understood that the function of the relays is to 95 maintain the succeeding contactor to be actuated in its open position until the current traversing that portion of the motor circuit, which includes the actuating coil for the relay, decreases to a predetermined value and permits the relay to shunt the resistor. After the contactor is closed, the reinsertion 100 of the resistor in the circuit of the actuating coil will not cause the contactor to open because the current traversing the resistor is 105 sufficient to maintain the contactor in its closed position.

The portion of the control circuit illustrated in Fig. 2 illustrates this same general principle as applied to control circuits embodying any desired number of contactors 110 actuated by a single relay.

Either of these systems of control may be employed for operating any electrical apparatus requiring a plurality of contactors 115 operated in accordance with certain electrical conditions and in a given sequence. The order in which the contactors close is controlled by arranging interlocks on the respective contactors or between contactors controlled by different relays. In this manner, any desired sequence of operation of the series of contactors can be established.

Although I have described a simple and preferred form of my invention with a 125 single modification, it will be understood that other applications are possible, and I desire, therefore, that only such limitations shall be imposed as are indicated in the appended 130 claims.

I claim as my invention:

1. A control circuit comprising a group of electromagnetically-controlled switches, a resistor in the control circuit of said switches to prevent the actuation of said switches, a relay adapted to effect the actuation of said switches by temporarily rendering said resistor ineffective, a second group of switches, a second relay for effecting the actuation of said second group of switches, operating coils for said relays, and interlocking means for subjecting said coils alternately to the motor current.
2. A system of control comprising a main circuit, a relay actuated by a predetermined value of current traversing a portion of said main circuit, means for diverting current from said portion of said main circuit, means for reestablishing a main flow of current through said portion of said main circuit, a plurality of switches for controlling said main circuit, electromagnetic coils for controlling the operation of said switches, a resistor in circuit with said coils for preventing the operation of said switches but permitting said switches to be maintained in the respective positions to which they have been actuated, said relay being adapted to effect the actuation of said switches by temporarily rendering said resistor ineffective.
3. A system of control comprising a main circuit, a relay actuated by a predetermined value of current traversing a portion of said circuit, a second relay actuated by a predetermined value of current traversing a second portion of said circuit, means for diverting current from one portion of said circuit to the other portion of said circuit, a group of switches controlled by said first relay for controlling said main circuit, coils for controlling the operation of said switches, a resistor in circuit with said coils and adapted to prevent the operation of said switches but permitting said switches to be maintained in the position to which they have been actuated, a second group of switches controlled by said second relay,

and interlocking means controlled by said second group of switches for controlling the sequence of operation of said first group of switches.

4. A system of control comprising a main circuit, a relay actuated by current of a predetermined value traversing a portion of said circuit, a second relay actuated by current of a predetermined value traversing a second portion of said circuit, a plurality of switches controlled by said relays for controlling said main circuit adapted to successively divert current from one portion of said circuit to said second portion of said circuit, coils for controlling the operation of said switches, resistors in circuit with certain groups of said coils for preventing sufficient energization of said coils to actuate said switches but permitting sufficient energization of said coils to maintain said switches in the positions to which they have been actuated, said relays being adapted to effect the actuation of said switches by rendering said resistors temporarily ineffective, and interlocking means for effecting the actuation of switches controlled by said coils alternately from said groups in accordance with a given sequence.

5. The combination with a motor having an armature and an accelerating resistor therefor, of an accelerating coil in series relation with said resistor, a second accelerating coil for connection in shunt relation to the first named accelerating coil and means for alternately diverting current from said coils.

6. The combination with a motor having an armature and an accelerating resistor therefor, of an accelerating coil in series relation with said resistor, a second accelerating coil, and means for diverting the motor current through said coils alternately and through different portions of said resistor.

In testimony whereof, I have hereunto subscribed my name this 24th day of Oct. 1919.

RAY E. DE CAMP.
